U.S. Appl. No. 29/527,301, filed May 18, 2015, Klein.

Primary Examiner — David G Muller*Assistant Examiner* — Nathan M Johnston(74) Attorney, Agent, or Firm — Stinson Leonard Street LLP(57) CLAIM

The ornamental design for over door accessory hooks, as shown and described.

DESCRIPTION

FIG. 1 is a front perspective view of the over door accessory hooks;

FIG. 2 is a front elevation view thereof;

FIG. 3 is a rear elevation view thereof;

FIG. 4 is right side elevation view thereof;

FIG. 5 is a left side elevation view thereof;

FIG. 6 is a top plan view thereof; and,

FIG. 7 is a bottom plan view thereof.

The over door accessory hooks is shown with a symbolic break in its length. The appearance of any portion of the article between the break lines forms no part of the claimed design.

1 Claim, 4 Drawing Sheets(56)
